COUPLER AND DRAFT GEAR

Frank H. Kayler, Alliance, Ohio, assignor to
American Steel Foundries, Chicago, Ill., a cor-
poration of New Jersey

Application February 28, 1929, Serial No. 343,263

17 Claims. (Cl. 213—12)

This invention pertains to railway rolling stock, and more particularly to improvements in draft appliances for use on railway cars.

In the earliest developments in railway draft gears that employed frictional resisting elements, it was the practice to employ wedge means positioned between and housed within two longitudinal beams positioned under the car that constituted the car sill. As the need for an increased capacity in railroad cars grew and with the development of improved locomotives with larger pulling capacity, the need for a draft gear with an increased capacity was also occasioned. The standard car designs provide for a specific type of car sill with a definite space between the beams thereof, which prevented satisfaction of this need by merely increasing the size of the devices used at that time. If such a practice were followed, the car sills would have necessarily been increased to a size unduly large and expensive and out of proportion to the other uses for the sills in car construction.

One answer to these requirements was the devising of draft gear employing frictional wedging members which have at least two sides in frictional contact for a single wedge, and have a sufficient capacity for efficient operation on cars of increased capacity, and can be installed for operation in connection with the standard A. R. A. car sill, all as particularly set forth and described in Patent No. 1,644,658.

There is another type of draft gear which embodies very desirable and advantageous features, which draft gear is known as the swivel butt arrangement and comprises means disposed between the coupler butt and the draft gear or yoke, providing maximum bearing area for the transmission of buff stresses, particularly between the coupler and draft gear.

It is therefore an object of this invention to provide a draft gear which embodies all the advantages of the first type of draft gear in addition to all of the advantages of the swivel butt arrangement of draft gear.

Another object of the invention is to provide a draft gear having a plurality of maximum bearing area means for transmitting stresses through maximum areas from the coupler to the draft gear in either buff or draft, the bearing area means including members providing maximum resistance to movement of the coupler in either draft or buff.

A further object is to provide a yoke for a draft gear, said yoke being provided with a means

providing maximum area for transmission of stresses from the coupler to the draft gear.

A still further object is to provide a draft appliance of the first type which is adapted to be used with the usual Farlow type of coupler, means being provided cooperating with the coupler and draft gear whereby a maximum area is provided for the transmission of stresses from the coupler to the draft gear.

With these and various other objects in view, the invention may consist of certain novel features of construction and operation, as will be more fully described and particularly pointed out in the specification, drawings and claims appended hereto.

In the drawings, which illustrate an embodiment of the device and wherein like reference characters are used to designate like parts—

Figure 1 is a fragmentary sectional top plan view of a portion of the draft sill and associated structure of a railway car provided with a draft appliance which is the subject-matter of this invention;

Figure 2 is a top plan view, similar to Figure 1, showing the position of cooperation between the various elements of the draft gear, yoke and coupler under a position of draft;

Figure 3 is a top plan view, similar to Figure 1, showing the position of cooperation between the various elements of the draft gear, yoke and coupler under a position of buff;

Figure 4 is an enlarged fragmentary sectional side elevation of the buffing piece, the same being taken substantially in the plane as indicated by the line 4—4 of Figure 2;

Figure 5 is an enlarged fragmentary side elevation of a portion of the draft sills and one of the wedge blocks of the draft gear, showing the cooperating guiding elements of the wedge block, the same being taken substantially in the plane as indicated by the line 5—5 of Figure 2; and

Figure 6 is an enlarged sectional end elevation of the parts indicated in Figure 5, taken substantially at right angles thereto, the same being taken substantially in the plane as indicated by the line 6—6 of Figure 2.

The draft sills 10 of the car structure are shown as secured at the body bolster 12 through the angles 14, securing means, such as the rivets 16, being common to the center bearing casting 18 which is additionally secured as by rivets 20 to the draft sills, said casting extending toward the end of the car to a point adjacent the aligned keyways 22 and being provided with members 24 forming stops, said members being spaced apart,

the web 26 in the casting being provided with a slot 28 forming a guide for the yoke 30 when the same is under buff, all as particularly described in copending application Serial No. 333,757, filed 5 January 21, 1929, Patent No. 1,947,056, February 13, 1934, by A. H. Oelkers, for Draft gear. Additional stops 32 are provided facing the stops 24 and adjacent the aligned keyways 22, stops 32 being between the keyway 22 and keyways 34 10 provided in the draft sills. Keyways 34 may be reinforced by portions of the striking casting 36, said striking casting being also provided with bearing 38 for the coupler 40, the coupler shown being of the Farlow type provided with a horizontal keyway 42 for the reception of a horizontally disposed key 44 extending through keyway 42, aligned keyways 34, and aligned keyways 46 provided in the yoke 30. The coupler butt is provided with an aperture 48 terminating in a recess 50 provided therein, said aperture and recess being for the reception of the forwardly extending prong of the Farlow draft gear.

Yoke 30 is of the vertical plane type and is provided with a rear wall 52 having an arcuate bearing portion 54 adapted to have cooperative engagement with a complementary bearing portion 56 provided on the draft block 58. The draft block 58 is provided with portions 60 extending through the apertures 22, said portions 60 having upwardly and downwardly extending guide portions 62 and 64 disposed on the outside of the vertical webs of the draft sills 10, strengthening reinforcements 66 being provided at any convenient points therein. Bearing or draft block 58 is provided with sloping or wedge portions 68 terminating in a flat portion 70, portions 68 having bearing engagement with corresponding sloping portions of the transversely disposed bearing blocks 70, said bearing blocks 70 having spring 40 seats 72 thereon and aligned apertures 74 therethrough for the reception of the securing rod or bar 76 provided with proper securing means and a spring cap, between which cap and spring seats a plurality of springs 78 and 80 are provided, 45 which springs may be regulated through the cap to place the draft gear blocks under an initial compression.

Draft block 82 is provided to complete the friction element assembly, said draft block being provided with sloping faces 84 of substantially the same angularity as the faces 68 and cooperating with corresponding faces on the friction blocks 70, the draft block 82 being provided with sill engaging members 86 corresponding to the 55 outwardly extending portions 60 of the friction block 58. The friction block 82 is provided with an arcuate bearing surface 88 terminating in recesses 90, said bearing surface 88 being adapted to have cooperative engagement with a complementary bearing surface on the buffing piece 92, said buffing piece having outwardly extending legs 94 provided with hook portions 96 for engaging the stops 32 under certain conditions of angularity. The buffing piece shown is provided 60 with a forwardly extending prong 98 of the usual Farlow type, said prong being adapted to extend within the aperture 48 and the recess 50 and serving as a guide between the buffing piece and the coupler butt.

70 In draft, (Figure 2), it will be seen that the coupler 40 moves forward and away from the buffing piece 92, which however is retained in position by cooperation between the lugs 96 of the legs 94 and the stops 32. The coupler may 75 continue in its forward movement until the key

44 contacts the end of the keyway 34, shown as provided by the striker casting 36. The key 44 however moves the yoke 30 in a forward direction, causing movement of the friction block 58 through the arcuate surfaces 54 and 56. This movement causes the friction blocks 58 and 82 to approach each other as the block 82 is limited in its forward movement by the stops 32. This movement then moves the friction blocks 70 outwardly, compressing the springs 78 and 80 to resist movement of the coupler. With this arrangement, the coupler 40 is free to move to an angled position, as movement to this angled position under draft, as illustrated in Figure 2, merely moves the yoke in positions following the coupler, the bearing areas 54 and 56 between the yoke and the friction block 58 remaining constant whereby a maximum surface of stress transmission is provided.

In buff, the coupler butt moves the friction block 82 away from the stops 32 toward block 58 held by the stops 24, thereby moving the friction blocks 70 outwardly, compressing the springs 78 and 80, thereby offering resistance to movement of the coupler. Should then the coupler be angled, as shown in Figure 3, the yoke follows positions of the coupler, it being understood that in buff the end of the yoke is moved into the slot 28 and away from the friction block 58, movement of the friction block having been arrested by the stops 24. In angled position, the coupler butt retains its bearing with the corresponding face of the buffing piece 92, there having been only relative movement between the arcuate faces provided on the friction block 82 and the buffing piece 92, but due to these arcuate faces, the bearing surface remains constant, thus providing maximum bearing area for stress transmission between the yoke and draft gear.

It will thus be seen that a very efficient, compact and advantageous draft gear is provided and one which has many advantages as has been apparent, and it is to be understood that I do not wish to be limited by the exact embodiment of the device shown, which is merely by way of illustration and not limitation, as various and other forms of the device will of course be apparent to those skilled in the art without departing from the spirit of the invention or the scope of the claims.

I claim:

1. In a draft appliance, the combination of sills having stops thereon, a yoke having spaced arms and a hooded end, draft gear disposed between said arms and having cooperative relation with said stops for stress transmission to said sills, a coupler movably secured to said hooded end, a member cooperating with said coupler and draft gear, said member being disposed between said yoke arms and having a larger dimension than said hooded end whereby said member will never enter said hooded end, said member having an arcuate surface cooperating with a complementary surface on said draft gear whereby a substantially constant buff transmitting surface is provided between said coupler and draft gear, and legs provided on said member extending into pockets formed on said draft gear adjacent certain of said stops, said legs normally contacting said stops to center said member and coupler.

2. In draft appliance, the combination of center draft sills, stops on said sills, a coupler member formed with a coupler shank, a draft gear having cooperating friction members associated with said sills and engaging with said stops,

- 5 a draft yoke associated with said gear and connected to said shank, and a buffing piece engaging said coupler shank and having swiveling movement relative to said draft gear to provide substantially constant bearing area for the transmission of forces therebetween while permitting angling of said coupler member, said buffing piece being held in association with said draft gear by said stops when said coupler member is in draft.

10 3. In a draft appliance, the combination of center draft sills, stops on said sills, a draft yoke between said sills, a coupler member formed with a coupler stem connected to said yoke and having relative movement therewith, a draft gear in cooperative relation with said yoke and including a plurality of friction members engaging the stops on said sills, and a buffing piece movable relative to said stem and a friction member, said buffing piece being associated with said stem and friction member and having an arcuate bearing surface cooperating with a complementary bearing surface provided on said friction member to provide a substantially constant bearing area with said friction member for the transmission of buffing forces therebetween while permitting angling of said coupler member, said buffing piece engaging the stops on said sills and being held in association with said draft gear thereby when said coupler member is in draft.

15 4. In draft appliance, the combination of center draft sills having oppositely disposed slots, stop members adjacent said slots, a coupler member formed with a coupler shank, a draft gear having cooperating friction members received in said slots and associated with said stops, and means cooperating with said coupler shank and draft gear to provide substantially constant bearing area for the transmission of forces therebetween while permitting angling of said coupler member, said means including a draft yoke connected to said coupler stem, and a buffing piece between said stem and said draft gear movable relative thereto and cooperating with said stem, said buffing piece having an arcuate surface cooperating with a complementary surface on a friction member of said gear, said buffing piece having parts adapted to engage certain of said stops for holding the same in association with said friction member when said coupler is in draft.

20 5. A friction block for a draft appliance, comprising a body portion formed with an arcuate bearing surface, said arcuate surface terminating in recesses.

25 6. A friction block for a draft appliance, comprising a wedge shaped body portion, an arcuate bearing surface provided on the forward part of said body portion, said arcuate surface terminating in recesses.

30 7. In a draft appliance, the combination of a friction block having an arcuate bearing surface, and a buffing piece associated with said block and having a complementary arcuate surface cooperating with the arcuate surface of said block.

35 8. In a draft appliance, the combination of a draft gear member having an arcuate bearing surface, said arcuate surface terminating in recesses, and a buffing piece associated with said member and having a complementary arcuate surface cooperating with the arcuate surface of said member, said buffing piece having parts extending into said recesses.

40 9. In draft appliance, the combination of draft sills provided with stops, a draft gear including cooperating friction members associated with said sills and stops, one of said members being formed with an arcuate surface, and a buffing piece having a complementary arcuate surface cooperating with the arcuate surface of said member and having parts interposed between said stops and said member whereby said buffing piece is held in association therewith during draft.

45 10. In draft appliance, the combination of draft sills provided with stops, a draft gear including cooperating friction members associated with said sills and stops, one of said members being formed with an arcuate surface, said arcuate surface terminating in recesses, and a buffing piece having a complementary arcuate surface cooperating with the arcuate surface of said member, said surface having parts extending into said recesses and disposed between said stops and said member whereby said buffing piece is held in association therewith during draft.

50 11. In draft appliance, the combination of center sills, a draft gear including cooperating friction members between said sills, a yoke embracing said members, and means for guiding said draft gear and yoke, said means including a slotted backstop member, and guide portions on certain of said friction members engageable with said center sills.

55 12. In draft appliance, the combination of center sills, a draft gear including cooperating members between said sills, a slotted backstop member between said sills, one of said friction members being formed with a recess disposed in opposite relation with the slot of said backstop member, certain of said friction members being formed with guide portions engageable with said center sills for maintaining said recess in opposite relation to said slot, and a yoke embracing said friction members and having a part engaging in said recess to permit angling thereof, said part being guided in said slot during transmission of buffing forces.

60 13. In draft appliance, the combination of slotted draft sills, a draft gear between said sills and including friction members extending outwardly through said slots, and guide means for said members disposed exteriorly of said sills, said guide means cooperating with said sills for holding said draft gear against lateral displacement during operation thereof.

65 14. In draft appliance, the combination of slotted draft sills, a draft gear including forward and rear wedge members, and guide members on said wedge members and exteriorly of said sills adapted to cooperate with said sills for holding said draft gear against lateral displacement during operation thereof.

70 15. In draft appliance, the combination of draft sills provided with stops, a coupler member having a shank, a draft gear associated with said sills and having a forwardly disposed member adapted to engage with said stops, and a buffing piece movable between said shank and draft gear and cooperating with the same to provide substantially constant bearing area for transmission of buffing forces irrespective of the angling of said coupler member, said buffing piece having parts disposed between said stops and said draft gear member whereby said buffing piece is held in association therewith when said coupler is in draft.

75 16. In draft appliance, the combination of draft sills provided with stops, a draft gear associated with said sills and stops and including a forwardly disposed member, said member being formed with an arcuate surface and engaging with said stops, and a buffing piece having a com-
